US00D654902S

(12) **United States Design Patent**
Chung

(10) **Patent No.:** **US D654,902 S**
(45) **Date of Patent:** **** Feb. 28, 2012**

(54) **MOBILE PHONE**

(75) Inventor: **Jin-Man Chung**, Goyang-si (KR)
(73) Assignee: **Samsung Electronics Co., Ltd. (KR)**
(**) Term: **14 Years**
(21) Appl. No.: **29/398,119**
(22) Filed: **Jul. 26, 2011**

(30) **Foreign Application Priority Data**

Apr. 22, 2011 (KR) 30-2011-0016581
(51) **LOC (9) Cl.** **14-03**
(52) **U.S. Cl.** ..... **D14/138 AD**
(58) **Field of Classification Search** ..... D14/138 AD,
D14/138 G, 138 R, 138 AC, 138 C, 496,
D14/341, 345, 346, 203.7, 247, 248, 218,
D14/138 AA, 138 AB; 455/575.1, 556.2,
455/556.1, 575.4, 566; D10/65; D13/168
